UNITED STATES PATENT OFFICE.

JAMES F. EVERETT, OF CHICAGO, ILLINOIS, ASSIGNOR OF ONE-FIFTH TO BERNARD F. SCHMIDT, ONE-FIFTH TO GEORGE W. FORD, ONE-FIFTH TO CHARLES W. BURROWS, AND ONE-FIFTH TO WILLIAM T. DELIHANT, ALL OF CHICAGO, ILLINOIS.

WASHING MACHINE.

Application filed March 24, 1924. Serial No. 701,416.

To all whom it may concern:

Be it known that I, JAMES F. EVERETT, a citizen of the United States, and a resident of the city of Chicago, county of Cook, and 5 State of Illinois, have invented certain new and useful Improvements in Washing Machines, of which the following is a specification.

My invention relates to improvements in 10 washing machines and more particularly to the door arrangement thereof, the object of the invention being to provide a simple, efficient door arrangement for such machines.

Other objects will appear hereinafter. 15 The invention consists in the combinations and arrangements of parts hereinafter described and claimed.

The invention will be best understood by reference to the accompanying drawings 20 forming a part of this specification, and in which,

Fig. 1 is a side view of a washing machine equipped with a door arrangement embodying the invention,

25 Fig. 2 is a detail face view of the door in the washing chamber proper,

Fig. 3 is a partial face view corresponding with Fig. 1, and

Fig. 4 is a section taken on line 4—4 of 30 Fig. 3 but showing doors in open positions.

The preferred form of construction as illustrated in the drawings comprises a spherical outer casing 5 having an upwardly swinging door 6 giving access thereto. The 35 door 6 is arranged to be locked in closed position by means of swinging bolts 7 engaging through slotted lugs 8 on the sides of said door as shown. The door 6 is also provided with a central supplemental peep door 9 which may be readily opened to obtain a view of the interior of the washing 40 machine.

The door 6 is mounted to swing by means of spaced arms 10 secured to said door and 45 mounted to swing freely on a rocker shaft 11 mounted in brackets 12 secured to the top of the casing 5 adjacent the door opening, said door being free to swing and permit the rocker shaft 11 to swing independently thereof. A suitable rest 13 is provided on the top of the casing 5 to support the door 6 in convenient open position as shown in Fig. 4.

A rotating perforated spherical washing

chamber 14 is mounted in casing 5 and provided with an upwardly swinging door 15 adapted and arranged to swing through the door opening in casing 5. The door 15 is provided with spring latches 16 of any usual or desired construction and is mounted to 60 swing on hinges 17. The door 15 also carries a strap 18 adapted and arranged to engage a hook 19 secured to the rocker shaft 11 to lock the door 15 in open position as indicated in Fig. 4. The rocker shaft 11 is provided with a crank handle 20 for manipulating the same.

By this arrangement both doors may be 65 fully opened and securely held in open positions while the clothes are being placed in 70 or removed from the washing chamber. The specific form and arrangement of the parts constitutes a simple and effective one for the purpose.

While I have illustrated and described the 75 preferred form of construction for carrying my invention into effect, this is capable of variation and modification without departing from the spirit of the invention. I, therefore, do not wish to be limited to the 80 precise details of construction set forth, but desire to avail myself of such variations and modifications as come within the scope of the appended claims.

Having described my invention what I 85 claim as new and desire to secure by Letters Patent is:

1. A washing machine comprising an outer casing; a washing chamber mounted to rotate in said casing; a door for said casing; a pivotal mounting for said casing door; a door for said washing chamber; a pivotal mounting for said washing chamber door so positioned and arranged as to permit the door to swing through the door opening in said casing; and a lock for said chamber door mounted on the pivotal mounting of said casing door and arranged to engage said chamber door when opened, substantially as described.

2. A washing machine comprising an outer casing; a washing chamber mounted to rotate in said casing; a door for said casing; a rocker shaft mounted on said casing; a loose pivotal mounting for said door on said rocker shaft; a hook on said rocker shaft; a door for said washing chamber arranged to swing through the door opening in said

- casing; and means on said washing chamber door arranged to engage the hook on said rocker shaft to lock said washing chamber in open position, substantially as described.
5. 3. A washing machine comprising an outer casing; a washing chamber mounted to rotate in said casing; a door for said casing; a rocker shaft mounted on said casing; spaced arms secured to said door and loosely pivoted on said rocker shaft; a hook on said rocker shaft between said arms; a door for said washing chamber arranged to swing through the door opening in said casing; and means on said washing chamber door arranged to engage the hook on said rocker shaft to lock said washing chamber door in open position, substantially as described.
- 10 15 20 25 30 35 40 45 50
4. A washing machine comprising an outer casing; a washing chamber mounted to rotate in said casing; a door for said casing; a rocker shaft mounted on said casing; spaced arms secured to said door and loosely pivoted on said rocker shaft; a hook on said rocker shaft between said arms; a door for said washing chamber pivoted to swing through the door opening in said casing; and a strap on said washing chamber door adapted and arranged to be engaged by said hook on said rocker shaft, substantially as described.
- In testimony whereof I have signed my name to this specification.
- JAMES F. EVERETT.
